UNITED STATES PATENT OFFICE.

GUIDO M. SACERDOTE, OF NEW YORK, N. Y.

ROLLING SCREEN.

Application filed February 13, 1923. Serial No. 618,762.

To all whom it may concern:

Be it known that I, GUIDO M. SACERDOTE, a subject of the King of Italy (declarant of intention of becoming a citizen of the 5 United States), residing in the borough of Queens, city of New York, county of Queens, and State of New York, have invented certain new and useful Improvements in Rolling Screens, of which the following is a full, clear, and exact description, reference being had to the accompanying drawings, forming a part of this specification.

This invention relates to improvements in 15 the construction of window screens or shades of the rolling type, being particularly adapted for use in connection with rolling screens.

Its primary object is to provide a positive and efficient locking mechanism for the 20 sides of the screen or shade, preventing its bulging or pulling out of the side guides under pressure.

A further object of this invention is to 25 provide a novel and improved type of locking mechanism for window screens or shades of the rolling type, whereby the screen or shade may be locked at any position against the action of a spring roller to which the 30 same is attached, and may simultaneously be locked at the sides against bulging or pulling out at the sides.

A still further object is to provide an improved construction of clamping means for 35 the sides of a rolling screen or shade, whereby wear and tear of the screen or shade itself is prevented.

With these and other objects in view, as 40 will more fully appear as the description proceeds, this invention furthermore consists in certain novel and improved constructions and arrangements of parts, as will be hereafter fully described and claimed in the appended claims.

45 In the construction of screens of this character, considerable difficulty has been heretofore experienced in preventing the screen from bulging or pulling out at the sides under the action of wind pressure or careless 50 handling, as well as from sagging at the sides under the action of the tension which is permanently applied between the top and the bottom of the same. This type of screens generally consists of a strip of wire 55 cloth attached at one end to a spring roller on which the same is wound when in opera-

tive, being concealed from view by a casing within which said roller is ordinarily mounted. The free end of the cloth is attached to a cross member which is used to operate the screen, and which is generally guided so as to constantly remain parallel to itself during its motion, thus exerting an even tension on said cloth throughout its entire length.

In order to cause the screen to stretch and to lie flat throughout the entire window space, however, the roller is maintained under tension at all times; and under this tension, unless prevented from doing so, the sides of the screen will sag, and the surface 70 of the cloth and its texture will in time become permanently deformed, interfering with the proper winding and unwinding of the same.

Various means have heretofore been devised, therefore, to prevent inward motion of the sides of the screen. In some instances, hooks or other retaining means have been attached to the sides of the screen, and compelled to travel along a predetermined 75 course by guiding means; but anything which is attached to the screen, inevitably causes increase and unevenness of the diameter of the same in winding, while it is extremely desirable, in devices of this kind, 80 to reduce said diameter to as small and unobtrusive dimensions as possible. Furthermore, those retaining means which are attached to the screen at intervals, cause the 85 side tension to be concentrated at their points of attachment, and may cause distortion and tear of the flimsy fabric of which the screen is generally composed.

In other instances, means for clamping the sides throughout their entire length have 90 been adopted, which I have found to be fairly effective, but which are open to various objections. Among these, are the necessity of a separate and additional operation of said clamping means subsequent to 95 the setting of the screen in position, and the use of operating means for the same which are not concealed and which mar the appearance of the screen. Another objection is the 100 wearing out of the sides of the screen, which 105 will in time occur, due to the rubbing action of wedge acting clamping means applied directly against the screen's surface.

My invention obviates these various unsatisfactory features by providing locking 110 means for the sides of the screen which will neither alter its physical condition, nor in-

crease its diameter when winding; and by providing locking means against the action of the roller, which operate simultaneously and in conjunction with said side locking means. I also provide a novel and simple method of guiding the motion of the cross member or bottom rail, which does away with a number of parts now used for this purpose in the construction of screens of various descriptions.

A specific embodiment of my invention is shown in the drawings, which are intended for illustrative purposes, and not in a limiting sense. In the same:

15 Fig. 1 is a front view in elevation of my improved screen applied to a window, in its extended position;

20 Fig. 2 is a fragmentary front view in elevation of the upper right hand corner of said screen;

25 Fig. 3 is a fragmentary side sectional view of the same;

30 Fig. 4 is a fragmentary plan sectional view of the same;

35 Fig. 5 is a plan sectional view similar to Fig. 4, showing the side of the wire cloth released by the clamping means;

40 Fig. 6 is a fragmentary front view in elevation, partly sectioned, of one of the ends of the bottom rail; and,

45 Fig. 7 is a detail sectional view of a side rail showing a different mechanism for operating the clamping means.

The frame of the screen consists of two uprights or side rails 10, 11, and a cross member or casing 12, which is shown at the top, and within which is mounted roller 13.

50 While said three members may be connected to each other in a permanent manner, I prefer to adopt a construction which allows of the various parts to be separated and reassembled at will; this construction possessing marked advantages in packing and shipping operations. Accordingly, I show each side rail attached to the casing by means of an angle piece 14, 15; each angle piece supporting one end of shaft 16, on which roller 13 is rotatably mounted.

55 Each angle piece is provided with an inwardly extending portion 17 which fits and is inserted within one of the ends of casing 12, and a longitudinally extending portion 18 which in a similar manner fits and is inserted within one of the ends of one of the side rails.

60 The two angle pieces and the casing are held together by means of two tie rods 19, 20, and by a third tie rod 21, which is inserted through a bead formed at 22 in the casing and which also stiffens the casing itself. Connection between each angle piece and its side rail is maintained by means of a tie rod 23 which also acts as a pivot for the clamping member, as will be explained.

65 The side rails are in the form of an en-

closed casing formed with a slot 24 between its rear and its inner sides; and casing 12 is formed with a slot 25 between bead 22 and rear side 26, which registers with slots 24 when the frame is assembled.

70 A spiral spring 27, one end of which is attached to shaft 16, and the other end to roller 13, is set under tension, and maintains in the roller a tendency to wind up the wire cloth 28 which is attached to the same. To the free end of said wire cloth is attached the bottom rail 29, by means of which the same may be extended or contracted, said cloth passing through slot 25 and having its sides extending through slots 30 24 within the side rails.

75 The wire cloth is attached to the bottom rail in any suitable manner. Through its various features of construction, the bottom rail is enabled to perform three different 85 functions, viz:

1.—Operating the cloth with an even tension for its entire width, the bottom rail being maintained constantly parallel to itself during its motion by having its ends 90 sliding along longitudinal guides.

2.—Locking the cloth at any position against the tension of the spring roller by means causing friction to take place between said bottom rail and its side longitudinal guides.

3.—Operating the side clamping means.

The clamping pressure proper, at the sides, is exerted by the wedging action of the cam surface 30 of a clamping rail 31, 100 inserted on tie rod 23, and capable of pivotal motion thereon; said clamping rail being thus mounted within the side rail and extending for practically its entire length.

105 Angular motion of said clamping rail around its pivot, will cause its cam surface 30 to press against or to release the surface against which the same abuts; which may, if desired, be the wire cloth itself, which would thus be clamped between the back of the side rail and the clamping rail, but which would be subjected to a rubbing action during the clamping operation.

110 To prevent the wear on the cloth which might possibly ensue, I prefer to employ a clamping leaf 32, pivoted at 33, receiving the pressure exerted by the clamping rail and clamping the wire cloth against the back of the side rail without any rubbing action. I also prefer to provide said leaf with a packing of material having a certain degree of resiliency and plasticity, preferably rubber, as shown at 34. Such a material will not only create better frictional conditions on account of its higher coefficient, but it will actually fill the spaces between the wires of the wire cloth, and actually lock the same against side motion.

115 120 125 130 Clamping rail 31 is formed with a beaded

edge 35 by means of which the rail is operated and which serves at the same time as a longitudinal guide for the bottom rail.

To this end the bottom rail is made collapsible and provided at each end with an arm 36 inserted through slot 34 and extending up to an end 37 inserted on said beaded edge 35 and slidably and pivotally movable thereon. By moving the two arms 36 inwardly or outwardly at the same time, therefore, the two clamping rails will simultaneously release or lock the sides of the wire cloth. Furthermore, if the pressure exerted by said arms 36 against the 15 clamping rail to move the same to its clamping position is maintained, the same will create a friction between said arms 36 and the clamping rails which will effectively lock the bottom rail preventing 20 rewinding of the cloth until said pressure is released.

In the device illustrated, the clamping action takes place when the two arms 36 are expanded, said outward movement of the 25 arms being caused in any suitable manner, for instance by means of springs as shown in the drawings.

In the same, arms 36 are slidably mounted within the bottom rail proper, and are each 30 provided with a rod 38 extending toward the center of the rail and terminating in an exposed clip 39. A spring 40 between the central portion of the rail and the rear of each arm 36 tends to force said arm outwardly, and exerts the pressure necessary to 35 operate the clamping rail connected thereto and to lock the bottom rail in position.

By applying the thumb and the tip of the first finger to the two clips 39, same may be 40 forced towards each other, moving arms 36 inwardly, and therefore releasing the clamping action; at the same time, the bottom rail may be operated so as to lower or to raise 45 the screen to its new position, when by releasing the clips the screen will again become locked.

The lower edge of the bottom rail is preferably provided with means for holding 50 a rubber blade 41 insuring a tight closure of the screen when in operating position, for instance a slot 42 through which said rubber blade may be inserted. Felt may also be used if desired.

The essential advantage of my invention 55 resides in the fact that a positive side locking action is obtained simultaneously with and through the action of locking the bottom rail, no separate control being required; the design of the locking mechanism itself, 60 however, may vary from the one shown, which is the preferred type on account of its simplicity.

To illustrate this point, in Fig. 7 I show 65 another of the various alternative ways in which the invention might be reduced to

practice. In the same, the side rail is secured to the angle piece by means of tie rods 43, 44; 45 designates the wire cloth, 46 a clamping leaf pivoted at 47, and 48 a packing with which the same is preferably provided. 70

Like in the previous case, the bottom rail is made collapsible, 49 designating one of its movable arms provided with an end portion 50 slidably and pivotally connected to a 75 longitudinal bar 51, integral with arms 52 hinged inside of the side rail at 53. Bars 51, one at each side of the screen frame, thus constitute the guiding means for the bottom rail, as well as its locking means when the 80 same is allowed or caused to expand.

The clamping leaf, 46, is in this case operated by means of a toggle joint constituted by arms 54 pivoted to said leaf at 55, pivotally connected at 56 to arms 57 attached to a fixed pivot 58 inside of the side rail. When the toggle joint is expanded, as shown in the drawing, the clamping action takes place, and when the same is contracted, by moving its joint 56 towards the left, clamping leaf 46 with its packing or pad 48 is caused to release the wire cloth which will thus be free to move. 90

The toggle joint is operated by arms 52 through connections 59 between said arms 95 and joint 56, and its operation is therefore simultaneous with, and controlled by the operation of the bottom rail.

In the devices shown in the drawings, I 100 use springs in order to create the pressure necessary to produce the clamping action, and the required frictional resistance between the bottom rail and its guiding bars, the springs being for convenience of construction, located in the inside of the bottom 105 rail. Both the cam and the toggle joint action described multiply the pressure exerted by the spring manifold, so that in practice I have found springs of moderate pressure and such as to be easily operated 110 by a woman in the manner described, to be quite satisfactory.

In such cases where more than normal pressure should be required, for instance, in 115 connection with windows of abnormal dimensions, means other than springs may of course be used to control the expansion or contraction of the bottom rail. It may also be noted that when springs are used, or other means as well, the same do not necessarily 120 have to be located in the bottom rail in order to obtain the desired result.

From the foregoing it is seen that I provide a novel form of control for locking 125 the sides of the wire cloth; clamping means of novel design for effecting the clamping action; a novel and simple method of guiding the longitudinal motion of the bottom rail; a novel method of locking the bottom rail; and a novel method of simultaneous 130

control of the bottom rail and the side clamping members.

As previously stated, the specific details of construction may vary from those shown without departing from the spirit of my invention; and I reserve myself the right to carry my invention into practice introducing all those changes and modifications which might be deemed advisable in order to satisfy varying conditions, and such as may enter, fairly into the scope of the appended claims.

I claim:

1. In a device of the class described, comprising a movable panel and a cross member attached thereto, means operated by said cross member adapted to lock the edges of said panel.
2. In a device of the class described, comprising a movable panel, means adapted to clamp the edges thereof, and means causing the automatic simultaneous operation of said clamping means.
3. As a new article of manufacture, a rolling screen or shade having automatically and simultaneously operated edge locking means, independent of said screen.
4. In a device of the class described, comprising a frame and a panel movable within the same, a cross member attached to said panel registering with parts of said frame and guided by said frame parts in the course of its longitudinal travel, so as to occupy substantially parallel successive positions during said travel.
5. In a device of the class described, and in combination with a frame and a panel movable within the same, a cross member attached to said panel having movable end pieces registering with parts of said frame and guided by said frame parts in the course of the longitudinal travel of said cross member, causing said cross member to occupy substantially parallel successive positions during said travel, and means for maintaining said end pieces under pressure against said parts.
6. In a device of the class described, and in combination with a frame and a panel movable within the same, a cross member attached to said panel, and side edge locking means for said panel controlled by said cross member.
7. In a device of the class described, and in combination with a frame and a panel movable within the same, a cross member attached to said panel having movable end pieces, and side edge locking means for said panel connected to and operated by said end pieces.
8. In a device of the class described, and in combination with a frame and a panel movable within the same, a cross member attached to said panel having movable end pieces, and longitudinal guiding means

therefor, movable therewith, causing the locking or the releasing of the edges of said panel.

9. In a device of the class described, and in combination with a frame and a panel movable within the same, a pivotally mounted edge locking member at each side thereof, and means for causing the automatic simultaneous operation of said locking members.

10. In a device of the class described, and in combination with a frame, a panel movable within the same, a cross member attached to said panel, and means for locking the side edges of said panel, means for simultaneously operating said cross member and said edge locking means.

11. In a device of the class described, and in combination with a frame, a panel movable within the same, a cross member attached to said panel, and means for locking the side edges of said panel, means for locking said cross member in position at the same time operating said edge locking means.

12. In a device of the class described, and in combination with a frame, a panel movable within the same, a cross member attached to said panel, and longitudinal guiding means therefor, means for causing a braking action between said cross member and said guiding means, and means for locking the edges of said panel simultaneously operated by said guiding means.

13. In a device of the class described, and in combination with a frame and a panel movable within the same, means for locking the edges of said panel, and a cross member attached to said panel having spring controlled movable end pieces operating said edge locking means.

14. In a device of the class described, and in combination with a frame having two side members, and a panel movable within the same having its edges registering with said side members, a clamping jaw at each side thereof adapted to clamp said edges against said frame side members, and spring controlled means for simultaneously operating the same.

15. In a device of the class described, and in combination with a frame having two side members, and a panel movable within the same having its edges registering with said side members, a clamping member at each side thereof adapted to clamp said edges against said frame side members, and a cross member attached to said panel adapted to operate said clamping members.

16. In a device of the class described, and in combination with a movable panel, and side edge clamping members therefor, a collapsible cross member attached to said panel adapted to operate said edge locking members.

17. In a device of the class described, a

frame having two side members, a panel movable within the same having its edges running through said side members, locking means for said edges enclosed within said side members; and a cross member attached to said panel operating said locking means.

18. In a device of the class described, a frame having two side members, a panel movable within the same having its edges running through said side members, locking means for said edges enclosed within said side members, and a collapsible cross member attached to said panel pivotally and slidably connected to said locking means.

19. As a new article of manufacture, a rolling screen or shade comprising a frame having two side members and a panel movable within the same having its edges running through said side members, and provided with longitudinal independent side edge clamping means entirely concealed within said side frame members.

20. The combination, with a frame, a

panel movable therein, and winding means for said panel, of a cross member attached to said panel, means adapted to lock the edges of said panel, and means adapted to lock said cross member in position and to operate said edge locking means.

21. The combination, with a frame, a panel movable therein, and winding means for said panel, of a cross member attached to said panel, means adapted to lock the edges thereof, and spring actuated means adapted to lock said cross member in position and to operate said edge locking means.

22. A rolling screen or shade comprising a frame, a spring roller mounted therein, a flexible panel attached thereto and adapted to be wound upon or unwound from said roller, means for locking the edges of said panel, and a self-locking cross member attached to the free end of said panel adapted to operate said edge locking means.

GUIDO M. SACERDOTE.
